Carlos P. Griffin ATTORNEY.

UNITED STATES PATENT OFFICE.

HARRY T. ROBERTS, OF OAKLAND, CALIFORNIA.

AUTOMATIC SPARK-ADVANCING MECHANISM.

1,274,082.

Specification of Letters Patent. Patented July 30, 1918.

Application filed August 22, 1916. Serial No. 116,376.

To all whom it may concern:

Be it known that I, HARRY T. ROBERTS, a citizen of the United States, residing at Oakland, in the county of Alameda, State of California, have invented a new and useful Automatic Spark-Advancing Mechanism, of which the following is a specification in such full and clear terms as will enable those skilled in the art to construct and use the same.

This invention relates to an automatic mechanism for advancing the time of sparking of the ignition system of an explosion engine with respect to the position of travel of the engine piston, any suitable type of current supplying apparatus being used in conjunction therewith.

An embodiment of the invention is shown in the drawing in which the same reference numeral is applied to the same portion throughout, but I am aware that there may be many modifications thereof,

Figure 1 is a side elevation of a portion of an engine showing this apparatus applied thereto, the casing containing it and a portion of the device being shown in vertical section,

Fig. 2 is a transverse sectional view of the advancing mechanism,

Fig. 3 is a front elevation of the brush carrying disk,

Fig. 4 is a back elevation of the distributor disk showing segments for the distribution of current to a four cylinder motor,

Fig. 5 is a side elevation of the advancing mechanism,

Fig. 6 is a transverse sectional view of the device on the line 6—6, Fig. 1 showing the distributor in the advanced position, and

Fig. 7 is a side elevation of the sleeve carrying the advancing mechanism.

The numeral 1 indicates a portion of the engine, 2 being a shaft suitably timed to deliver current to the distributor cables 3, 4, 5 and 6 which extend to suitable apparatus, not shown, for the production of high tension current. The distributor 12 to which the cables 3 to 6 inclusive are connected has metallic segments 13, 14, 15 and 16 to which said cables are electrically connected, and it is provided with other metallic segments 17, 18, 19 and 20 which are insulated from each other and from the other segments for the reason that the material of which the disk 12 is made and into which said segments are

sunk is of fiber or other similar insulating material.

The advancing mechanism is mounted on a shell or sleeve 21, said sleeve having lugs 22, 23 which lugs receive a pin 24. The pin 24 forms a pivot for the two steel or other suitable springs or other equivalent elements 25, 26, which tend to close when at rest, expanding under the influence of the segmental weights 27, 28, 29, 30 and 31 when the engine is running. The sleeve 21 is mounted on the shaft 2 and secured thereto by means of a pin 32 or in any other suitable manner and on the outer end said sleeve supports a disk 33, said disk being held in place thereon by means of a small nut 34 which permits said disk to rotate with respect to the sleeve.

The weight 31 is provided with a link 34 which link has a pin 35 connected therewith and with the disk 33. The disk 33 is provided with a hollow or other contact making brush 36 and with a felt brush 37 which keeps the track on which the brush 36 travels clean, said brushes having springs to hold them engaged with the segments on the disk 12 being constructed in a well known manner. The pin 35 is connected into the disk 33 by means of the hole 38 and said disk has a stop pin 39 on its back to prevent the advancing mechanism from pulling the disk 33 around more than a given amount, the lug 22 acting as a stop for said pin.

Surrounding the advancing mechanism is a fiber shell or other suitable means 40 which is held in place on a suitable projecting flange 41 of the engine by means of suitable springs 42, 43. The disk 12 fits into the cover 40 and is secured in place therein by means of two springs 44, 45 which are connected with the shell 40 and a pin 46 prevents the disk from being inserted in place in any position save that one in which it should be placed. Thumb holds 47, 48 are provided on the spring 44, 45 to enable them to be released from the disk 12.

In operation the current is delivered from a suitable source of supply to a wire grounded upon the frame of the engine and is thence delivered by way of the brush 36 to the segments and cables 3 to 6 inclusive. The springs 25 and 26 and the segmental weights 27, 28, 29, 30, and 31 constitute a centrifugal device adapted to expand through centrifugal force as the speed of the time shaft increases and to contract or

move inwardly under the influence of the springs when the speed of the shaft decreases. When the engine is at rest the springs 25, 26 tend to close up and hold the 5 weights in close engagement with the sleeve on which they ride, but when the engine is running the segments will tend to expand the springs to the position shown in Fig. 6, whereupon the link 34 will draw the disk 33 10 around to advance the time of the making and breaking of the electric current delivered to the cables 3 to 6 inclusive. As soon as the engine slows down the spark advancing mechanism will slow down and retard 15 the spark, thereby meeting all conditions of engine driving.

The pin 39 may be placed in either of the holes 50 or 51 to give a larger or smaller advance as the engine may require.

20 Having thus described my invention what I claim as new and desire to secure by Letters Patent of the United States, is as follows, express reservation being made of permissible modifications:

25 1. A spark advancing mechanism for explosion engines comprising a suitably timed shaft, a revoluble shell connected with said shaft, a contact supporting disk carried by said shell and movable with respect to the 30 same, a series of weights surrounding said shell, springs to hold said weights normally in engagement with the shell, means to rotate the weights with the shell, a link connecting said weights with the disk whereby 35 the disk will be advanced as the weights move outwardly from the shell under the influence of rotation, and a series of contact segments over which the contact travels.

2. A spark advancing mechanism for explosion engines comprising a suitably timed shaft, a shell rigidly connected therewith, a series of weights surrounding said shell, springs adapted to hold said weights normally against the shell, means connected 45 with one end of the springs to rotate the weights with said shell while permitting the other end of said springs to move outwardly under the influence of rotation, a contact disk movably supported on the shell, a link 50 connecting said disk and one of said weights whereby the contact disk will be advanced as the shell is rotated, a series of contact segments, and a brush carried by the disk and adapted to travel over said contact segments.

3. A spark advancing mechanism for explosion engines comprising a suitably timed shaft, a shell rigidly connected therewith, a set of weights surrounding said shell, springs 60 holding the weights normally in contact with the shell and pivoted thereto at one end of the springs, a contact disk carried by the shell and movable with respect thereto, a link connecting one of the weights with said 65 disk and adapted to shift the position of said

disk with respect to the shell, a series of contact segments, and a brush carried by the contact disk adapted to pass over said contact segments.

4. A spark advancing mechanism for explosion engines comprising a timed shaft, a shell carried thereby, a contact supporting disk movable on the shell, a set of weights around the shell, a pair of springs adapted to hold the weights in contact with the shell, 70 a pin to which one end of the springs are hinged, the other ends being movable outwardly when rotated, a link connecting the weights and contact disk, an insulating cover for the shell, a disk secured to said cover 75 and having a plurality of contact segments over which the contact travels.

5. A spark advancing mechanism comprising a timed shaft, a shell carried thereby, a series of weights around the shell, a pair of 80 circular springs inclosing the weights and holding them in contact with the shell, a pin carried by the shell and to which said springs are pivoted at one end, a contact supporting disk movable on the shell, a link 85 connecting the weights and disk to advance the latter, and a series of contact segments over which the contact travels.

6. A spark advancing mechanism for explosive engines comprising a suitably timed 90 shaft, a contact supporting member rotating with the shaft and having a limited rotary movement with respect to the same, and a rotary centrifugal device arranged concentric with the shaft and connected at one 95 end with the same and at the other end with the said member and including a curved series of segmental weights adapted to be thrown outwardly by centrifugal force as the speed of the shaft increases, and springs 100 connecting the weights and adapted to move the same inwardly as the speed of the shaft decreases.

7. In an electric ignition for explosive engines, a rotary contact, a plurality of contacts arranged in the path of the rotary contact to coact therewith, to close the circuit, a rotary member for actuating the rotary contact and controlling means operated by the rotary member to advance the rotary contact and the spark proportionately to the increase in the speed of the engine, said controlling means including a spring arranged substantially concentric with the axis of rotation of the rotary member and weights arranged to expand the spring by centrifugal force as the speed increases, said spring being automatically movable inwardly as the speed decreases.

8. An automatic spark producing and advancing mechanism comprising a revoluble member timed to the engine, a low tension contact brush, a spring encircling said member for advancing and retarding the low tension contact brush, and a series of con- 125

- tact segments arranged in a circle opposite the low tension contact brush and coacting therewith to close the circuit for advancing and retarding a high tension contact brush.
- 5 9. An automatic spark producing and advancing mechanism comprising a revoluble member timed to the engine, two springs holding each a series of weights encircling said member each spring fastened to said member at one end on opposite sides of said member and other end of said springs are connected to brush holders made to balance said mechanism under the influence of rotation.
- 10 10. An automatic spark producing and advancing mechanism comprising a revoluble member timed to the engine, two springs holding each a series of weights encircling said member, two brush holders and brushes a flexible line for each brush holder, one end of said line connected to a brush holder the other end to a free or outwardly movable end of springs or weights.
- 15 11. An automatic spark producing and advancing mechanism comprising a revoluble member timed to the engine, a pair of springs, a pair of series of weights surrounding said member, a pair of brushes and brush holders, a pair of round disks fastened 20 to the revoluble member on one side of each of said springs and weights as shields for said springs and weights.
- 25 12. A spark advancing mechanism comprising a suitably timed shaft, a shell carried thereby, a disk supporting brush or brushes which connects to commutator with segments thereon, said disk being movable on said shell by rotation and connection of weights fashioned thereto and said disk being insulated at the connection of said segments and commutator for the purpose of 30 doing away with the arc or flame at said contact at the time of parting, which arc or flame is caused by electric current being 35 broken.
- 40 13. A spark advancing mechanism for explosion engines, comprising a suitably timed shaft, a shell carried thereby, a series of weights surrounding said shell connected at one end to said shell and other end of said weight, connected to a disk supporting contact brush or brushes by means of a connecting link, whereby under the influence of rotation, said weights open outwardly and leave an open space, which said weights are 45 thrown out of balance in their path of rotation, and beside of this path of rotation on said shell is a disk supporting contact brush or brushes which is mounted on said shell movably and which part of said disk be constructed heavier in one part than the other, and whereby the heavier part is brought 50 into place beside of weight rotation path by said connecting link to counteract the open space in the rotation of said weights, 55 when same are in outwardly position, and when in a closed up position said heavier part of said disk moves in a relative position to said weights, which has a tendency 60 to counteract the balance of said mechanisms 65 when in rotation.
- 70 14. An automatic spark producing apparatus for explosive engines comprising a revoluble member timed to the engine, a series of contacts, a brush carried by the timed member to contact with the said contacts, and a weighted curved spring arranged substantially concentric with the revoluble member and connected at one end and having its other end free and connected with 75 the said brush, said spring being movable outwardly by centrifugal force and inwardly by its spring action for automatically advancing and retarding the spark as 80 the speed of the said member increases and 85 decreases.

In testimony whereof I have hereunto set my hand this 16th day of August, A. D. 1916.

HARRY T. ROBERTS.
